MEANS FOR TRUING MANDRELS

Joseph Sunnen, Kirkwood, Mo.

Application July 28, 1934, Serial No. 737,365

2 Claims. (Cl. 125—11)

My invention has relation to improvements in methods of and means for truing the mandrels of machines for grinding pin holes and it consists in the novel features more fully set forth in the specification and pointed out in the claims.

When the mandrels of grinding machines, such as shown in my Patent No. 1,913,689, dated June 13, 1933, and my pending application Serial No. 655,392, filed under date of February 6, 1933, have been put to considerable use, both the abrasive element and the guide elements of the mandrel naturally undergo wear, such that the surfaces of the elements that contact with the work are no longer true in the sense that all points along a given line lengthwise of each element lie in a common plane. Due to the movement of the work back and forth over the mandrel the elements in time develop high and low points which if permitted to remain interfere with the grinding of a true hole. It, therefore, becomes necessary from time to time to correct these irregularities of wear and again restore the mandrel to perfect condition. This perfect condition requires that the surfaces of the stone and guide elements that are to contact with the work must not only be rectilinear from end to end thereof, but should also be longitudinally parallel and transversely curved along the circumference of a common circle. In other words, these contacting surfaces should lie on the surface of a common cylinder.

It is the object of the present invention to provide a method of truing a pin hole grinder mandrel to accomplish the above requirements and also the means whereby said method is practiced. This object and the manner of accomplishing the same will be better apparent from a detailed description of the same in connection with the accompanying drawing, in which:

Figure 1 represents a grinding machine embodying a mandrel of the type set forth in the patent and application aforesaid with the truing means applied to said mandrel; Fig. 2 is a perspective view of the truing means herein designated as a truing sleeve; and Fig. 3 is a cross-section through the mandrel and truing sleeve applied thereto, said section being taken on the line 3—3 of Fig. 1.

Referring to the drawing, G represents a grinding machine embodying a driving spindle S in which is secured the mandrel M to which the work (not shown) is applied. As above stated, from time to time the grinding stone or abrasive element 1 and the guide elements 2, 2 of the

mandrel have to be trued or restored to perfect condition to eliminate the irregularities of wear. For this purpose, I have provided a cylindrical sleeve 3 (preferably of cast iron) of substantial thickness, the inner surface 4 of which being truly cylindrical and of an initial diameter slightly more than the diameter of a circle in which the contacting surfaces of the elements 1 and 2 rotate when adjusted to their innermost position, or for application to the smallest size of hole for which the mandrel is designed.

The sleeve 3 is of substantial thickness so that it may have a long life in view of the fact that its inner surface is gradually worn away by the abrasive contact with the elements 1 and 2. A slot 5 is provided in the wall of the sleeve 3, said slot extending substantially the entire length of the sleeve (as shown in Fig. 2) and somewhat around the circumference thereof so as to follow the path of a helix. The pitch of the helix is not critical but need be just sufficient to produce a shearing effect between the leading edges of the elements and the rear edge of the slot with respect to their relative rotation when the sleeve is applied to the mandrel for the purpose of truing the same. The slot 5 further serves as a discharge opening through which the particles of the grinding stone 1 and guide elements 2, 2 liberated from these elements during the abrading action are discharged from the cylinder.

In the practice of my truing method and operation of the sleeve 3, the latter is applied to the mandrel M and the mandrel then caused to rotate in the same manner as when it is used for grinding the pin hole in a piston or other piece of machinery. As the mandrel rotates the operator grasps the sleeve 3 firmly and slowly reciprocates the same from end to end of guide elements 1 and 2 of the mandrel. During the rotation of the mandrel and the reciprocation of the sleeve 3 the grinding stone 1 is advanced in the same manner as when the mandrel is applied for the purpose of regrinding a piston pin hole. In other words, the action of the mandrel M is the same with respect to the sleeve 3 as it is with respect to a piece of work, the pin hole of which is being trued.

During this action, owing to the length of the sleeve 3, which is somewhat greater than one-half the length of the mandrel elements 1 and 2, the high places (or points of greatest diameter across the mandrel) will first contact with the sleeve 3 and be worn down. Said lines of contact between the elements 1 and 2 and the sleeve

3 gradually lengthen until contact is made between said elements and the sleeve throughout the entire length of the sleeve. Owing to the length of the sleeve it is not possible for the 5 same to be rocked on the mandrel M, but it will be moved backward and forward in parallelism with the rotation axis of said mandrel. Thus, after the truing operation has continued for a sufficient length of time the contacting surfaces 10 of the grinding stone 1 and guide elements 2, will have been ground to truly cylindrical form, corresponding with the inner surface 4 of the sleeve 3. As the abrading action between the sleeve 3 and elements 1 and 2 proceeds the particles liberated from said elements by this action 15 will be continually discharged through the slot 5 so that they cannot work around within the sleeve 3 and score the elements 1 and 2. The direction of rotation of the mandrel during the 20 truing action is the same as when the mandrel is used for grinding piston pin holes, as indicated by the arrows in Figs. 1 and 3. When the mandrel M is rotated in the direction of the arrow (Fig. 3) the edge *a* is the leading edge of the 25 grinding stone 1 and the edges *b*, *b* are the leading edges of the guide elements 2, 2. Obviously, these edges travel toward the edge *c* of the slot 5 and if said slot were disposed parallel to the longitudinal axis of the sleeve 3 the edge *c* would

impinge against the entire length of the edges *a* and *b* at the same time and momentarily stick together so that pieces would be broken from the guide elements when the contacting edges again freed themselves. It is to avoid this objectionable result that the slot 5 is inclined, as shown in Fig. 2.

Having described my invention, I claim:

1. In grinding machines having a grinding mandrel composed of a longitudinally extending 10 abrading element and longitudinally extending guide elements, the combination of a truing sleeve having a longitudinally extending slot thru the wall thereof, the edge between one wall of the slot and the inner surface of the sleeve forming a dressing edge for the abrading element when the abrading element is rotated within the sleeve in contact with the walls thereof.

15 2. In grinding machines having a grinding mandrel composed of a longitudinally extending 20 abrading element and longitudinally extending guide elements, the combination of a truing sleeve having a helically disposed slot thru the wall thereof, the edge between one wall of the slot and the inner surface of the sleeve forming 25 a dressing edge for the abrading element when the abrading element is rotated within the sleeve in contact with the walls thereof.

JOSEPH SUNNEN.
